UNITED STATES PATENT OFFICE

2,543,554

PENCIL SHARPENER

Hugh M. McClure, Chicago, Ill.

Application August 12, 1947, Serial No. 768,129

3 Claims. (Cl. 120—89)

1

This invention relates to pencil sharpeners, and has for an object the provision of new and improved devices of this type.

More particularly the invention has for an object the provision of sharpening devices for shaping and pointing the leads of drafting pencils, or the like, wherein a needle or chisel point may be imparted to the lead without the exercise of skill or attention upon the part of the operator.

Another object of the invention is to provide in a device of this character, abrasive means arranged in such formation as to include spirally curved surfaces which shape without tendency to fracture a pencil point to a configuration ideal for drafting purposes.

Still another object of the invention is to provide a device having elongated trough means, substantially V-shaped in cross section, and wherein the walls defining the trough means diverge laterally and longitudinally from one end to the other, and are so contoured as to impart longitudinally extending opposed spiral curves to the said walls.

A still further object of the invention is to provide a holder for abrasive means, so constructed that application of the abrasive means thereto positions and shapes the abrasive means in a fashion to produce the characteristic operation of the device.

Still another object of the invention is to provide a holder wherein abrasive means employed in connection therewith, are readily attachable and replaceable, and wherein properties of the abrasive means are utilized for retaining the same in operative position.

Other and further objects of the invention will appear from the specification and claims, and from the accompanying drawings, in which:

Figure 1 is a perspective view illustrating the manner of use of an embodiment of the invention.

Figure 2 is a side elevational view of said embodiment.

Figure 3 is a top plan view of the illustrated embodiment.

Figure 4 is a transverse vertical sectional view, corresponding substantially to the line 4—4 of Figure 2.

Figure 5 is a view similar to Figure 4, and corresponding to the line 5—5 of Figure 2.

Figure 6 is a view similar to Figure 4, and corresponding to the line 6—6 of Figure 2.

Figure 7 is a perspective detailed view of an abrasive member employed in connection with the invention, while

Figure 8 shows a different embodiment of the invention.

As shown in Figures 1 through 7 of the drawing, the illustrated embodiment of the invention

2

comprises an elongated holder 10, preferably made of stainless steel, although the holder might be constructed of any other suitable material, such as plastic. The holder 10 is of elongated trough-like form, and in cross section is substantially acutely V-shaped, having a rounded apex portion 11, and side walls 12 and 13. From adjacent one end of the holder, indicated at 14, the side walls 12 and 13 diverge laterally and longitudinally at uniformly constantly changing angles, starting at the substantially parallel walls best shown in Figure 4, and gradually increasing, as shown in Figures 5 and 6, to a point adjacent the opposite end 15 of the holder 10. In addition to their lateral and longitudinal divergence, each of the walls 12 and 13 is concavo-convex, being gently curved laterally and longitudinally to produce a substantially spirally or helically curved contour 16 from one end 14 of the holder 10 to the other end 15 of said holder.

The apex portion 11, beyond the end portion 15, is provided with an extension 17, which is tilted from the apex portion 11 inwardly, as indicated at 18. The extension 17 is preferably triangular in shape when the holder 10 is viewed edgewise, with its attenuated portion 19, connected to the apex portion 11, and its broadened portion 20, extending outwardly from the end portion 15. The outer margins of the extension 17 are provided with upturned portions or flanges 21 and 22, these flanges being slightly tilted away from each other. An aperture 23 may be provided in the triangular extension 17, to provide means by which the holder 10 may be hung on a nail or the like.

Adapted for insertion into the holder 10, is a pair of abrasive strips or liners 24 and 25. These strips may be of any suitable kind, but preferably comprise cardboard strips of the type shown in Figures 1, 2, 3 and 7, ordinarily used for manicuring or filling the finger nails, and which are readily obtainable cheaply in the open market. The strips 24 and 25 are composed of relatively stiff but flexible cardboard, or similar material, and are provided upon their faces with an abrasive material indicated at 26. The strips 24 and 25 are obtainable in different breadths, thicknesses, and lengths. The breadth of the same in the present instance is not particularly important, so long as the strips are slightly broader than the walls 12 and 13. The strips 12 and 13, however, need to be, and are readily obtainable in, lengths somewhat greater than the length of the holder 10, exclusive of the extension 17. They should also be of a thickness so that the combined thicknesses of two will fit snugly between the walls 12 and 13 at the end 14 of the holder 10. These strips 24 and 25, when placed within the holder 10, with the abrasive surfaces 26 directed toward each other, and with one set

of ends between the walls 12 and 13, adjacent the end 14 of the holder 10, lie flat along the interior surfaces of the walls 12 and 13 and take the shape of said walls. Adjacent their opposite projecting ends 27 and 28, these ends are flexed outwardly about the flanges 21 and 22, respectively, of the extension 17, and by reason of the stiffness of the strips and their somewhat resilient flexibility, the strips are retained in spread apart position, as well as shaped to the spirally curved contours of the walls 12 and 13 of the holder 10.

It will be apparent that when the strips 24 and 25 are in position in the holder 10, the abrasive means comprising the surfaces 26, beginning near the flexed ends of these strips, provide a wide flaring entrance, and continuing past the extension 17 and between the walls 12 and 13, present spirally curved surfaces 29 and 30, arranged in an acute V-shaped formation, and which converge both laterally and longitudinally toward the end 14 of the holder 10.

With this construction, the point of a drafting pencil, for example, may enter the acutely V-shaped trough between the spirally arranged abrasive surfaces, and then be drawn through the trough. If it is desired to needle point the pencil, the pencil may be twirled on its own axis by the fingers during its passage through the trough; if a chisel point is desired, twirling of the pencil is omitted. In each case, the spirally curved abrasive surfaces simultaneously shape and gage the point, imparting a needle point or sharp edge toward the bottom of the trough, and tapering the point to a greater shaped thickness because of the divergent curved nature of the abrasive surfaces, so that a point ideally suitable for drafting purposes, is imparted to the lead. There is no tendency of the shaped point to break, either when it is being sharpened or after it has been sharpened. Not only do the spirally curved and acutely V-shaped abrasive surfaces shape the point, but it will be noted that the abrasive means themselves are shaped through the act of placing them within the holder, and of course the abrasive strips are readily replaceable when desired.

A somewhat different embodiment of the invention is illustrated in Figure 8. All parts are similar to those already described, except that in this embodiment walls 31 and 32 are made somewhat wider than the walls 12 and 13, and the extension 33 has no function except to provide a handle, or means by which the device may be hung upon a nail or the like. In this construction the abrasive means take the form of strips of emery cloth 34, one set of ends being clamped between the walls at the end 35 of the holder, and each strip 34 extending along its related wall of the holder, terminating at the opposite end 36 of the holder where it is clipped or held in place by a resilient fastener 37, prefer-

ably formed integrally with the related wall of the holder. In this construction, the walls 31 and 32 of the holder diverge laterally and longitudinally from the end 35 toward the end 36, and are curved laterally and longitudinally to provide the spiral curves heretofore referred to, and just before reaching the end 36, the walls 31 and 32, are flared as indicated at 38, to provide the relatively wide spirally curved entrance formation heretofore referred to in connection with Figures 1 through 7 and corresponding to the flared ends 27 and 28 of the strips 24 and 25.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

- 25 1. A device of the character described comprising a trough, a spreader extending from one end of said trough symmetrical therewith, a pair of pencil sharpening abrasive sheets lining said trough interiorly and together straddling said spreader in sprung apart relation for the convenient entrance of a pencil sharpened between said sheets.
- 30 2. An abrasive sheet holder comprising a trough the edges of which flare apart toward one end, an upturned sheet spreader extending from said one end said spreader serving to spring apart abrasive sheets disposed in said trough and hold same sprung against the flared apart edges of said trough.
- 35 3. An abrasive sheet holder having a trough in which abrasive sheets are retained opposing relation, and an upturned sheet spreader extending from one end of said trough symmetrical therewith said spreader serving to maintain responsive ends of such sheets in sprung apart relation for the convenient entry of work drawn between such sheets.

HUGH M. McCLURE.
